UNITED STATES PATENT OFFICE.

JOHN KLEINBACH, OF SPOKANE, WASHINGTON.

COMBINATION TOBACCO AND MATCH CONTAINER.

1,196,787.

Specification of Letters Patent.

Patented Sept. 5, 1916.

Application filed November 4, 1915. Serial No. 59,564.

To all whom it may concern:

Be it known that I, JOHN KLEINBACH, a citizen of the United States, residing at Spokane, in the county of Spokane and 5 State of Washington, have invented certain new and useful Improvements in Combination Tobacco and Match Containers, of which the following is a specification.

This invention relates to improvements 10 in combination tobacco and match boxes of that character in which a box is provided for the tobacco, the box having a lid or top hinged thereto, and there being a retainer for holding matches in the lid.

15 My invention consists more particularly in a novel form of retainer for the box top.

It is well known that matches, other than what is known as the safety matches, so deteriorate when subjected for a long time to 20 the fumes of any moist substance, that they lose their combustion properties and fail to ignite. It has been proposed to ship ordinary matches in a tobacco box but it has been found that this was impractical because of the deterioration of the heads of 25 the matches.

Now my invention has to do with an improved retainer which not only retains the matches in the top of the box, but which 30 also provides a safety striking surface whereby the matches may be ignited when desired for use.

A particularly novel feature of my invention is to provide the retainer with a 35 safety striking surface which is disposed adjacent to the matches when the latter are held in the match box top, but which is withdrawn from juxtaposition with the safety matches when it is desired to strike 40 a match. Thus the liability of sparks flying from the struck match to the other matches in the box top, is practically eliminated whereas if the striking surface were in close 45 juxtaposition to the safety matches, when a match was struck, the remaining matches would be very liable to ignite thereby resulting in total loss.

A further novel feature of my invention consists in providing a retainer which is 50 so proportioned with respect to the top of

the match box and which presents a continuous or imperforate surface such as will prevent even short pieces of matches falling out of the box top when the retainer is in position, it being understood that the usual 55 box top of a tobacco can is considerably longer than the average safety match.

A further object of my invention is to provide improved means for carrying the combination striking surface on the retainer, and a still further object of the invention is to provide a novel spring hinge designed and constructed to normally act and hold the retainer in either of its extreme positions. 65

Other objects and features of the invention will be more fully described in connection with the accompanying drawing and will be more particularly pointed out in and by the appended claims. 70

In the drawing:—Figure 1 is a perspective view of a tobacco box showing the top in an open position and illustrating the application of my improved retainer thereto. Fig. 2 is a sectional view showing the top 75 fully opened. Fig. 3 is a sectional view showing the top partially opened. Fig. 4 is a perspective view of my retainer detached from the tobacco box. Fig. 5 is a perspective view of a modified form of retainer. Fig. 6 is a plan view of a further modification of the retainer. 80

Like characters of reference designate similar parts throughout the different figures of the drawing. 85

As illustrated, 1 designates the body of a tobacco box which is provided with a rim 2 surrounding its upper open end. On one margin of the rim 2 there is formed a plurality of hinged butts 3 to accommodate the 90 spindle of the hinge whereby the top 4 is hinged to the box body 1. The top 4 is provided with hinge butts 5, as shown more particularly in Fig. 1. It will also be observed that the top 4 is a hollow body and 95 is capable of being used as a container and I utilize the container for holding matches 6.

My improved match retainer is indicated at 7 and the same comprises, in the preferred construction, an imperforate con- 100

tinuous plate of thin metal or like material which is substantially flat. At one margin I provide a finger grip 8, preferably on the end part and at one side margin I provide 5 a snap projection 9 which is adapted to be snapped into a recess 10, formed in one wall of the top 4. The provision of this expedient, enables me to positively hold the retainer in the position shown in Figs. 1 10 and 2. Now the retainer is provided with a pintle bail comprising pintle arms 11, projecting at right angles to the retainer 7, and a pintle portion 12 adapted to be extended through the butts 3 and 5, or adapted 15 to be in position so that the butts 3 and 5 will be formed about the pintle portion 12.

I do not claim broadly the idea of a retainer having an integral portion forming a pintle for hinging the retainer and the 20 top to the box body but I have invented certain new features along this broad idea. By having the pintle formed integral with the retainer, in the absence of any division of the pintle portion 12, I greatly cheapen the 25 construction and increase the efficiency of the hinge joint.

A part of the pintle portion 12 is shown flattened at 13, so as to have a cross-section somewhat increased with respect to the cross-section of the remainder of the pintle portion. The central butt 3, on the box body 1, is somewhat enlarged so as to grip this flattened portion 13 with a spring or resilient contact. The flattened portion 13 is so 35 located that when the match retainer is in overhanging relation with respect to the box body, this flattened portion will be gripped by the central butt 3 so as to hold it in such position and against free turning 40 movement which it would otherwise have. Now the importance of this feature will be brought out in connection with another feature which I will now describe.

A striking surface 14 is provided on the 45 retainer in such a manner and in such a position that when the retainer is in the position shown in Fig. 1, to retain the matches, the striking surface will lie adjacent the matches. Now when the top 4 is open as 50 shown in Fig. 2, and the match retainer is swung into overhanging relation with the top of the box 1, then the striking surface 14 will be not only located in an extensible position to strike a match, but it will be so 55 far removed from the matches in the top 4 that there will be no danger of flying sparks igniting the remaining matches. Furthermore, I claim to be the first to provide a striking surface of this character for 60 safety matches, in a box of this general type. In the preferred construction as shown in Fig. 4, a glue is applied to the metal surface and containing enough acid to eat into the

surface and then the striking composition is sprinkled over the glue and is thereby 65 retained.

In Fig. 5, the retainer is of the same construction except that the end margins 15 are bent back to grip the ends of a striking surface 16 which is mounted upon card- 70 board 17. I provide this form with the same kind of pintle bail as shown in Fig. 4, the bail being indicated as a whole at 18.

In the modified form shown in Fig. 6, the retainer comprises a frame 19 having 75 a pintle bail 20 and the frame surface is made continuous by the interposition of a foraminated surface 21.

Now there is a two-fold reason for the advantages to be obtained from this particular kind of a retainer, irrespective of the construction shown in Figs. 4, 5 and 6. In the first place, the retainer is designed and adapted for certain sizes of tobacco boxes which are already on the market and which 35 cannot be changed without changing the whole system of the manufacture. The boxes are so oblong in form that the lengths of the top are greatly in excess of the lengths of the safety match. In the next 90 place, a device of this character must be made so cheaply as to only add the slightest fraction of extra expense to the box and therefore it is desired to have a retainer composed of the least possible amount of 95 metal. Therefore, the problem involved was to hold matches in the top, irrespective as to the position of the match in the top, with a retainer which was greatly reduced in size with respect to the length of the top. 100 I have accomplished this by making a retainer which extends transversely across the top but only of such length as is necessary to prevent discharge of relatively short matches. In some embodiments, it might be 105 desirable to have a continuous retainer as shown in Fig. 6, and in other conditions, retainers as shown in Figs. 4 and 5, but in any event, the retainer is continuous instead of being skeleton in form. 110

It is believed that the novelty and utility of my invention will be fully understood from the foregoing description, and while I have herein shown and described one specific form of my invention, I do not wish 11 to be limited thereto except for such limitations as the claims may import.

I claim:—

1. In a box of the character described, a box body, a top hinged to said body and adapted to contain matches, a hinged retainer movable into said top to retain the matches therein and withdrawable from said top to permit of removal of matches therefrom, a striking surface on said retainer, marginal portions of said retainer

being bent over and upon said striking surface to anchor the same in position, substantially as described.

2. In a box of the character described, a box body, a top for said body, a match retainer having formed integral therewith a continuous pintle bail provided with a pintle portion, said body and top having hinged butts formed about said pintle por-

tion to hinge said match retainer and top 10 to said box, one part of said pintle portion being of enlarged cross-section for spring engagement with one of said butts to hold said match container in different positions, substantially as described. 15

In testimony whereof I affix my signature.

JOHN KLEINBACH.
